DENTAL ARTICULATOR

Bernard Weissman, 3406 Poplar St., Oceanside, N.Y.

Filed Aug. 26, 1959, Ser. No. 57,314

Term of patent 14 years

(Cl. D24—1)

FIG. 1 is a top perspective view taken from the front and left side of a dental articulator showing my new design, the undersides of the top and the base being substantially plain; and

FIG. 2 is a top perspective view taken from the rear and right side thereof.

I claim:

The ornamental design for a dental articulator, substantially as shown and described.
